UNITED STATES PATENT OFFICE.

LEE DE FOREST, OF NEW YORK, N. Y.

INDICATING DEVICE FOR FLUID TANKS.

Application filed June 13, 1919. Serial No. 304,034.

To all whom it may concern:

Be it known that I, LEE DE FOREST, a citizen of the United States, residing at New York, county and State of New York, have 5 made a certain new and useful Invention in Indicating Devices for Fluid Tanks, of which the following is a specification.

This invention relates to indicating devices for fluid tanks.

10 The object of the invention is to provide a device for indicating when a fluid contained in a tank is nearly completely drawn off or the tank has become empty.

15 A further object of the invention is to provide an indicating device particularly for use in connection with gasoline tanks for automobiles or the like which will give an audible signal when the gasoline has been nearly consumed.

20 Further objects of the invention will appear more fully hereinafter.

The invention consists substantially in the construction, combination, location and relative arrangement of parts, all as will be 25 more fully hereinafter set forth, as shown by the accompanying drawing, and finally pointed out in the appended claims.

Referring to the drawing:

Fig. 1 is a sectional view of a gasoline 30 tank equipped with an audible signal device embodying my invention.

Fig. 2 is a similar view of a slightly modified construction.

The same part is designated by the same 35 reference character wherever it occurs throughout the several views.

While I have shown and will now describe my invention as applied to a gasoline tank particularly adaptable for use on automobiles or other motor vehicles, I wish it to be 40 understood that the principle thereof is applicable for use in all arts where it is desired to obtain a signal when a fluid contained in a tank or container is nearly exhausted therefrom. It is among the special 45 purposes of my invention to provide an audible signal which becomes operative when the gasoline in the tank is withdrawn below a predetermined point therein. Referring 50 to Fig. 1 as illustrative of the principle of my invention, the tank is indicated at 1, in the bottom of which, and preferably in place of the usual drain cock or plug, I insert the end 2 of a tube, preferably flexible. 55 Into the end of the tube 10 which is 2 is inserted a small straight metal tube

4 extending practically the entire height of the tank 1. In the top of the tube 4 are a plurality of small holes or slits 3. Slidably mounted over the tube 4 is a sleeve 5 which is supported by means of arms 6 secured to the end of a float 7, likewise slidably mounted around the tube 4. The float 7 may be of any suitable material such as cork, balsa wood or the like, and is large enough in volume to lift the sleeve valve 5 upwards on the tube 4 to completely cover the holes or slits 3 in the tube when the fluid within the tank is sufficient in quantity to rise above the level of the float. The float 7 is not larger in diameter than the plug 2' which enables the assembled device illustrated in Fig. 1 to be inserted in the tank through the opening in which is seated the plug 2'. The tube 4 is in communication, as above explained, with the tube 10, which, as above stated, may be either flexible or metal, such as copper, which tube 10 extends under the bottom of the car to the position where it is desired to locate the signalling device. The end of the tube 10 has mounted thereon an ordinary air whistle 11 comprising a sealed cap with a small perforation or hole 12 therein. If desired a cut-off valve or cock 13 is inserted in the tube 10 at a point easy to be reached by the driver to shut off the noise of the whistle if it becomes annoying and after it has sounded its warning. The operation of the device is as follows: As long as the gas in the tank 15 is above a certain minimum amount, i. e., above the level of the float 7 it holds the float 7 up as far as the flange 14 at the end of the tube 4 will permit the sleeve 5 to go, thus covering the perforations 3 in the tube 4. When the gas gets below this minimum level, however, or the danger level, say three 20 gallons in the tank are left, then the float having dropped with the fluid and the sleeve valve dropping with it uncovers the holes 3 in the pipe 4. Since the air intake into the tank via the tube 10 and the whistle 12 is of considerably greater area than the usual pin hole in the cap or the tank air will be drawn into the tank through the 25 whistle 12 and make a shrill, piercing but not loud sound which will warn the driver that he is on his last measure of gasoline or, in the illustration above, on his last two or three gallons.

In Fig. 2 I show a slightly modified construction for actuating this audible whistle

signal. In this arrangement the tube 4 is supported by supporting arms 6 from the filling cap 15 of the tank located in the top of the tank 1, and the tube 4 has on the exterior of the cap the whistle 11 and the lower end of the tube extends to a point which is above the three gallon level in the tank or whatever other level desired to actuate the signal device when the cap 15 is screwed into place in the tank 1. In this arrangement I provide the usual hole 16 in the cap 15. So long as the gas level is above the lower end of the tube 4 the air coming into the tank must enter as usual through the hole 16 which leads into a tube 17. This tube is closed at the lower or flanged end and is provided with holes or perforations 18 near said end. The sleeve 5 in this instance which is slidably mounted on the tube 17 is connected by rod 19 to the float 7 which is slidably mounted on the tube 4. The flange 14 at the extreme end of the tube 17 limits the downward movement of the sleeve 5 so that when the float 7 drops with the fluid contained in the tank 1 the sleeve 5 will cover the holes 18 in the tube 17. As long as the gas level is above the float 7 the air coming into the tube must enter as above stated through the hole 16, but when the float drops the air inlet into the tank 1 is solely through the whistle 11 and tube 4, as the valve 5 covers the holes 18 in tube 17, and hence the whistle will blow. It is of course apparent that the sleeve 5 is controlled in its movements by the float 7 which in turn is controlled by the amount of fluid in the tank.

If desired, air inlets 3' may be provided in tube 4 near the lower end thereof to be covered and uncovered by float 7 in accordance with the level of the liquid and thereby cause the whistle to be operated or not.

It is obvious that the float 7 and the sleeve 5 may be dispensed with in the arrangement here shown inasmuch as the difference in the diameter of the respective tubes 17 and 4 render it unnecessary to close the small openings 18 in the tube 17 after the bottom of the tube 4 has been uncovered as this tube being of larger diameter than the tube 17 the air will rush in more readily through the tube 4 than through the tube 17 and thus actuate the whistle after the lower end of the tube 4 has been uncovered.

I have shown the whistle 11 as on the outside of the cap 15 but I do not wish to be limited or restricted in the particular location of the whistle, or the direction of the air therethrough. I have shown also a feed supply pipe 20 through which the liquid from the tank is caused to flow and thereby operate the whistle when the set liquid level is reached.

Many other changes in details will readily

occur to those skilled in the art without departing from the spirit and scope of my invention as defined in the claims, and therefore having set forth the objects and nature of my invention, and having shown and described specific structures embodying the principles thereof, what I claim as new and useful and of my own invention and desire to secure by Letters Patent is,—

1. The combination with a fluid tank, having a normally open air inlet thereto of restricted size, and a normally closed air inlet of comparatively larger size, a signalling device associated with said last mentioned inlet to be actuated by air passing therethrough, and means for opening said last mentioned inlet when the fluid in said tank has dropped below a predetermined point, and means actuated thereby for closing said first mentioned inlet.

2. The combination with a fluid tank, having a normally open air inlet thereto of restricted size and a normally closed air inlet of comparatively larger size, an audible signal device located in said last mentioned inlet to be actuated by air passing therethrough, and means for opening said last mentioned inlet when the fluid in said tank has dropped below a predetermined point, and means actuated thereby for closing said first mentioned inlet.

3. The combination with a fluid tank, having a normally open air inlet thereto of restricted size and a normally closed air inlet of comparatively larger size, an air whistle located in said last mentioned inlet and actuated by air passing therethrough, and means for opening said last mentioned inlet when the fluid in said tank has dropped below a predetermined level, and means actuated thereby for closing said first mentioned inlet.

4. The combination with a fluid tank, of an air tube extended within said tank, a whistle located on said tube to be actuated by air passing therethrough, and slideable means on said tube for causing said whistle to become operative.

5. The combination with a fluid tank, and a removable cap therefor, of a hollow tube carried by said cap, and extending therethrough, said tube being of such length that when said cap is in normal position relative to the tank, the end of the tube within the tank is out of contact therewith, a whistle associated with said tube to be actuated by air passing therethrough, and slideable means on said tube within the tank for causing said whistle to become operative or inoperative in accordance with the amount of fluid in the tank.

6. The combination with a fluid tank, and a removable cap therefor, of a hollow tube carried by said cap, and extending therethrough, said tube being of such length that

- when said cap is in normal position relative to the tank, the end of the tube within the tank is out of contact with the bottom thereof, and a whistle located in said tube to be actuated by air passing therethrough, a float slidably mounted on said tube, an auxiliary air inlet, and means controlled by said float for closing said auxiliary air inlet.
7. The combination with a fluid tank, and a removable cap therefor, of a hollow tube carried by said cap, and extending therethrough, said tube being of such length that when said cap is in normal position relative

to the tank, the end of the tube within the tank is out of contact with the bottom thereof, and a whistle located in said tube to be actuated by air passing therethrough, a float slidably mounted on said tube, an auxiliary air inlet, a valve for closing said auxiliary inlet, and a connection between said valve and float for obtaining simultaneous movement thereof.

In testimony whereof I have hereunto set my hand on this 31st day of May, A. D. 1919.

LEE DE FOREST.
